[57] CLAIM

The ornamental design for a hand racquet, substantially as shown.

DESCRIPTION

FIG. 1 is a perspective view of my new design for a hand racquet;

FIG. 2 is a top plan view of FIG. 1 showing the rear contour of the hand racquet;

FIG. 3 is an end elevational view as viewed from the left of FIG. 2;

FIG. 4 is an end elevational view as viewed from the right of FIG. 2;

FIG. 5 is a side elevational view taken along arrow A of FIG. 1;

FIG. 6 is a side elevational view taken along arrow B of FIG. 1; and

FIG. 7 is a bottom plan view of FIG. 1 showing the frontal hitting surface.
